United States Patent Office.

IMPROVEMENT IN FENCE.

BENJAMIN BILLINGS, OF LYONS, IOWA.

Letters Patent No. 60,127, dated December 4, 1866.

SPECIFICATION.

Be it known that I, BENJAMIN BILLINGS, of Lyons, Clinton county, and State of Iowa, have invented a new and useful method of constructing Portable Fences; and I do hereby declare that the following is a full, clear, and exact description of the construction and operation of the same, reference being had to the annexed drawings, making a part of this specification, in which—

Figure 1 is a section.

Figure 2, a longitudinal elevation of straight fence.

Figure 3, a view of a zigzag or Virginia fence.

Figure 4, a view of a circular or hurdle fence.

To enable others to make and use my invention, I will describe its construction and operation.

I make round balusters or pickets, which are put through holes bored through rails, as shown in *c c*, figs. 1, 2, 3, and 4; and for a straight fence, as fig. 2; I construct posts as at A, figs. 1 and 2, with a cap piece, D, which fits a tenon on the top of post A, and has a hole through the other end for picket to pass through, as at D, fig. 1; the picket, P, is let into the shoulder of the post, A, at bottom, as shown by the dotted lines. Now, I set the posts firmly in the ground, and bring the frames together, one rail above the other, and insert the picket, P, through the cap, D, the two top and two bottom rails to its place in the post, which holds the panels together and makes the fence firm. To accommodate the fence to the uneven surface of the ground, I cut a slot or mortise through the top rail, which gives the panels freedom to bend to the ground.

For a zigzag or Virginia fence, I simply set the panels at any required angle, and insert the picket, P, as shown in fig. 3; in order to keep the angles more firmly in their places, I put, from a picket of one panel to one in the other, a cross-brace, as at B, fig. 3.

For a circular or hurdle fence, I put the panels together as in a Virginia fence, putting in the picket at the angles, as shown in fig. 4.

Now, to take down, to remove any of these, I have but to remove the picket, P, and the panels can be at once loaded on a wagon and taken to another point and set up again, with no waste of lumber and but little time.

What I claim as my invention, and desire to secure by Letters Patent, is—

The arrangement of the post A, picket P, cap D, when constructed, arranged, and operating substantially as and for the purpose set forth.

BENJAMIN BILLINGS.
